UNITED STATES PATENT OFFICE.

THEODORE HERTWIG, OF NEW YORK, N. Y., ASSIGNOR TO FRANK WENTER,
OF CHICAGO, ILLINOIS.

DESIGN FOR A HALL HAT-RACK.

SPECIFICATION forming part of Design No. 17,180, dated March 15, 1887.

Application filed January 31, 1887. Serial No. 226,051. Term of patent 3½ years.

To all whom it may concern:

Be it known that I, THEODORE HERTWIG, a citizen of the United States of America, residing at New York, in the county of New York and State of New York, have invented and produced a new and original Design for Hall Hat-Racks, of which the following is a specification, reference being had therein to the accompanying drawing.

- 10 The leading features of my design are, first, the conventional representation of a street-lamp with a mirror and hat-rack; second, of a street-lamp with ladder, ring, and bowl, and, third, of the street-lamp, ladder, and chair.
- 15 The accompanying drawing represents a perspective view of my newly-designed hall hat-rack, in which A denotes the conventional representation of a street-lamp upon a post, a, with mirror b and hooks c. Against the lamp-post is leaning a ladder, B, with ring d. Ver-

tically below ring d is bowl D in the base of the hat-rack, also provided with chair E, having drawer f, and with railing e.

What I claim is—

1. The design for a hall hat-rack herein shown and described, consisting of mirror-frame A, being the conventional representation of a street-lamp, with hooks c, post a, ladder B, ring d, bowl D, and base C.

2. The design for a hall hat-rack herein shown and described, consisting of mirror-frame A, being the conventional representation of a street-lamp, with hooks c, post a, ladder B, ring d, bowl D, and chair E.

In testimony whereof I affix my signature in presence of two witnesses.

THEO. HERTWIG.
